UNITED STATES PATENT OFFICE.

CHESTER A. LATHAM, OF WICHITA, KANSAS.

BEARING.

SPECIFICATION forming part of Letters Patent No. 657,550, dated September 11, 1900.

Application filed October 8, 1898. Serial No. 693,018. (No model.)

To all whom it may concern:

Be it known that I, CHESTER A. LATHAM, a citizen of the United States of America, residing at Wichita, in the county of Sedgwick and State of Kansas, have invented certain new and useful Improvements in Bearings, of which the following is a specification, reference being had therein to the accompanying drawing, and the figures of reference thereon, forming a part of this specification, in which the figure is a sectional view of a box with rollers with ridges surrounding them in two directions and a shaft.

This invention relates to certain improvements in bearings; and it consists of rollers placed between the boxing and journal, said rollers having ridges surrounding them in both directions and the boxing with outlets in the under side; and the object of my invention is to produce a bearing that will run with the least possible friction.

Referring to the drawing, 1 represents a boxing.

2 represents a shaft.

3 represents rollers having ridges 4 and 5 running around said rollers in opposite directions from the ends toward the center. Said ridges may have a flat bearing-surface or they may have a round or oval bearing-surface. 6 represents a small space between said ridges 4 and 5. 7 represents the ends of said rollers, made either rounding or conical. 8 represents small openings in the under side of the boxing 1. 9 represents a collar, which 35 may be made in any suitable shape or form.

Said ridges surround said rollers in opposite directions for the purpose of preventing the tendency of an end thrust. Said openings 8 are to allow any foreign substance dropping out which would be worked to the center or 40 to either end by the ridges 4 and 5.

Having thus described my invention, what I claim as new and useful, and desire to secure by Letters Patent, is as follows:

1. In combination with a journal with a continuous smooth surface and a boxing with a continuous smooth surface, solid rollers having the rounded ends, a series of uniform spiral ridges surrounding said rollers from one end to a point near the center in one direction, a like series of spiral ridges surrounding said rollers in the opposite direction from the opposite end to a point near the center. 45

2. A journal with a continuous smooth surface, a boxing with a continuous smooth surface, and small openings in the under side for the purpose specified, solid rollers having rounded ends, a series of spiral ridges surrounding each of said rollers in one direction from one end to a point near the center, and 50 a series of like ridges surrounding each of said rollers in an opposite direction from the opposite end to a point near the center, and a suitable collar sleeved on said bearing at each end of said boxing and rollers, substantially as shown and described. 55

CHESTER A. LATHAM.
